UNITED STATES PATENT OFFICE.

WILLIAM DANIEL FERRIS, OF STERLING, ILLINOIS, ASSIGNOR TO THE DILLON-GRISWOLD WIRE COMPANY, OF STERLING, ILLINOIS.

WIRE-FENCING MACHINE.

No. 801,449.

Specification of Letters Patent.

Patented Oct. 10, 1905.

Application filed May 29, 1905. Serial No. 362,881.

To all whom it may concern:

Be it known that I, WILLIAM DANIEL FERRIS, of Sterling, Whiteside county, Illinois, have invented a new and useful Improvement in Machines for Making Wire Fencing, of which the following is a specification.

- The invention is a machine for making wire fencing of the type disclosed in United States Letters Patent No. 575,345, granted to John Wool Griswold January 19, 1897; and it consists in certain improvements upon the machine set forth in United States Letters Patent No. 604,041, granted to John Wool Griswold and Abel G. Goldthwait May 17, 1898.
- The said improvements consist, chiefly, in the construction whereby I am enabled to secure the ends of two successive pickets simultaneously to the strand-wires, thus, as herein-after explained, doubling the speed and capacity of the machine; also, in means for moving the spindles longitudinally during their coiling operation; also, in means for moving the picket-wires laterally into the first row of spindles; also, in the means for moving one tier of spindles out of the path of the strand-wires in order to permit free passage of the attached pickets; also, in the various combinations and instrumentalities more particularly pointed out in the claims.
- In the accompanying drawings, Figure 1 is a side elevation of the machine, taken in the direction of the arrow 1 on Fig. 2. Fig. 2 is a plan view of the machine, showing the devices for feeding in the strand-wires and for uniting the transverse or picket wires thereto, but not showing the device for feeding in the transverse or picket wires. Fig. 2^a is a similar view showing the device for feeding in the transverse or picket wires. The two drawings, Fig. 2 and Fig. 2^a, if placed together exhibit the whole machine in plan view. Fig. 3 is a side elevation of the machine, taken in the direction of the arrow 3, Fig. 2^a. Fig. 4 is a transverse section of the crimping device on the line 4-4 of Fig. 2. Fig. 5 is an end view of the crimping device and associated parts, taken on the line 5-5 of Fig. 2 and Fig. 4. Fig. 6 is a side elevation of the second tier of coiling-spindles and associated parts, taken on line 6-6 of Fig. 2 and Fig. 8. Fig. 7 is a longitudinal horizontal section taken on line 7-7 of Fig. 6. Fig. 8 is a transverse section taken on the line 8-8 of Fig. 2 and Fig. 6. Fig. 9 is a side elevation and partial sec-

tion of the first tier of coiling-spindles and associated parts, taken on the line 9-9 of Fig. 2; and Fig. 10 is an end view of the device shown in Fig. 9, taken on the line 10-10 of Fig. 9 and Fig. 2. Fig. 11 is a transverse section on the line 11-11 of Fig. 9. Fig. 12 is an end view taken on the line 12-12 of Fig. 6. Fig. 13 is a plan view of the device for cutting the transverse or picket wires. Fig. 14 is a cross-section on the line 14-14 of Fig. 13. Fig. 15 is a plan view of the feeding-block for the transverse or picket wires. Fig. 16 is a section on the line 16-16 of Fig. 15. Fig. 17 is a face view, and Fig. 18 an edge view, of the cam 29, which actuates the first tier of spindles to cause them to slide, and also of the cam 21, which operates the vibrating finger which moves the picket or transverse wire into engagement with said spindles. Fig. 19 is a face view, and Fig. 20 an edge view, of the cam 62, which actuates all three tiers of coiling-spindles. Fig. 21 is a face view, and Fig. 22 an edge view, of the cam 58, which actuates the mechanism which reels up the completed fence. Fig. 23 is a face view, and Fig. 24 an edge view, of the cam 73, which actuates the mechanism for cutting the transverse or picket wires. Fig. 25 is a face view, and Fig. 26 an edge view, of the cam 44, which actuates the mechanism for feeding in the transverse or picket wires. Fig. 27 is a face view, and Fig. 28 an edge view, of the cam 36, which actuates the mechanism for raising the frame which supports the third tier of coiling-spindles. Fig. 29 is a face view, and Fig. 30 an edge view, of the cam 34, which actuates the mechanism for causing the second tier of coiling-spindles to slide. Fig. 31 is a face view, and Fig. 32 an edge view, of the cam 71, which actuates the mechanism for crimping the strand-wires. Fig. 33 is a general diagrammatic view in plan, illustrating the operation of the machine.

Similar numbers and letters of reference indicate like parts.

Referring to Figs. 2 and 33, A B C D E F G H I J K represent strand-wires, and L M N O P the transverse or picket wires. The strand-wires A to K are fed forwardly through the machine, (from the right to left of the drawings Figs. 2 and 33.) The cross or picket wires L M N O P are fed transversely across the strand-wires.

The machine as a whole may broadly be

divided into two parts, the first part including all those devices which directly act upon the wire to feed it, to coil it, to cut it, to present it to the coiling devices to crimp it, and 5 the second part the mechanism through which these devices are actuated and which is timed so as to cause the aforesaid devices to operate in proper sequence and at proper intervals. I will first describe the devices included 10 in what I have designated as the "first" part of the machine.

The mode in which the picket-wires are attached to the strand-wires will be best understood from the diagram Fig. 33. There are 15 three tiers of coiling-spindles Q R S. The spindles Q of the first tier are placed in echelon. The spindles R and S, respectively, of the second and third tiers are in line abreast. The operating ends of the spindles of tiers Q 20 and R are turned rearwardly. The operating ends of the spindles of tier S are turned forwardly. Upon the strand-wires A C E G, &c., the ends of the pickets are coiled by the spindles R and S. Around the alternating 25 strand-wires B D F, &c., the middle parts of the pickets are coiled by the spindles of tier Q. All of the strand-wires are moved forward simultaneously, and all of the picket-wires are moved across the strand-wires simultaneously. 30

Consider first the picket-wire P. This is moved across the strand-wires A B C until it protrudes beyond C a distance p . The spindle Q, through which strand-wire B passes, 35 then rotates to coil the picket-wire P around said strand-wire, and then a cutting device (indicated at T) divides off a picket X, so that its end protrudes a distance q beyond strand-wire A. The pickets on A B C move onward 40 until the second tier of spindles R is reached. These spindles then coil the ends p q of each picket X around the strand-wires A C E G I K.

Consider next the picket-wire O. This is moved across the strand-wires A B C D E 45 until it protrudes beyond E a distance p' . The spindle Q, through which strand-wire D passes, then rotates to coil the picket-wire O around said strand-wire, and then a cutting device (indicated at T') divides off a 50 picket Y, so that the end protrudes a distance q' beyond strand-wire C. The pickets Y on C D E are not acted on by spindles R, but move onward until the third tier of spindles S is reached. The spindles S then coil 55 the ends p' q' of each picket Y around the strand-wires C E G I.

The pickets Y, which extend between strand-wires C E, for example, are staggered with respect to the pickets X, which extend between strand-wires A C, for example, and are separated therefrom by equal intervals.

As the strand-wires A B C D E move onward simultaneously and as the pickets are equidistantly spaced and staggered, as described, it results that at the same moment as

the spindles R coil the ends p q of the pickets X around the strand-wires A C the spindles S coil the ends p' q' of the pickets Y around the strand-wires C E.

The first and second tiers of coiling-spindles Q R.—One of these spindles (of either row Q or R) is shown in section at a, Fig. 7. It is tubular to permit passage of the strand-wire and carries a fixed pinion b and a grooved collar c , secured in place by nut d . On the 70 collar is a loose ring e , which receives the pivots of a yoke f . The shank of the coiling-head g is secured in the spindle by blind screw h . The coiling-pin i extends into a recess j in said head. The recess affords access to the inner end of the pin for purposes of adjustment. 80

First. The coiling-spindles Q of the first tier and associated parts are constructed as follows, Figs. 9, 10, 11: On the plate U are 85 bolted the spindle-boxes k . Journaled under the plate are as many shafts V as there are spindles. All of shafts V are actuated by bevel-gearing W from cross-shaft 17, Fig. 2, and transmit motion by pinions l to the spindle-pinions b . In this way all of the coiling-spindles Q are simultaneously rotated to coil the picket-wires around the strand-wires. 90

In order to move the picket-wires laterally beneath the pins of their coiling-spindles, 95 the following device is employed: Y' is a rock-shaft journaled in supports bolted with the spindle-boxes to plate U . On said shaft are loose sleeves 84, carrying curved fingers m , Fig. 9. Crank-arms n , loose on said sleeves, are connected by rods o to levers r on a rock-shaft 18. Extending from shaft 18 is an arm 19, carrying roller 20, which bears on cam 21 on main driving-shaft 22. The rotation of cam 21 vibrates shaft 18 and through the intermediate mechanism the arms n and fingers m . Each finger m which extends over a picket-wire then moves that wire laterally under the pin i of its coiling-spindle. The fingers are normally held up by the helical spring 11 23, one end of which is secured to the frame of the machine and the other end to an arm 24. (See dotted lines in Fig. 9 on shaft 18.)

In order to prevent the coils of the picket-wire fromlapping over one another, it is 11 necessary to impart to the coiling-spindle a longitudinal movement when in operation. This is done by yoke f , carried by arm s on sleeve t , which slides on shaft V , Fig. 9. Sleeve t is linked to arm u on rock-shaft 25, 12 which also has an arm 26. A helical spring 27 connects the end of arm 26 to any fixed abutment and holds a roller 28 on said arm in contact with cam 29 on shaft 22. Through this mechanism the rotation of cam 29 causes 12 the arm s to retract the spindle a in its box k as said spindle rotates to effect the coiling, thus causing the coils of the picket-wire, as L, Fig. 10, to be placed on the strand-wire, as B, Fig. 2, in regular succession. 13

Second. The coiling-spindles R of the second tier and associated parts are constructed as follows, Figs. 6, 7, and 8: Through these spindles only alternate strand-wires pass, as 5 A C E, &c. Between the side members of the frame extends the downwardly-flanged inclined cross-beam B', upon the upper side of which are bolted the spindle-boxes k'. Journaled in the beam-flanges are short shafts 10 C', each carrying combined spur and bevel pinion D'. The spur part of the pinion D' engages with the pinion b' of spindle R. The beveled part engages with the bevel-gears 30 on a cross-shaft E', journaled in side members 15 of the frame. The rotation of shaft E' therefore rotates all of the spindles R simultaneously to effect the coiling operation.

The object of placing spindles R in an inclined position is to get the strand-wires passing through them out of the way of the ends 20 of the pickets as the latter are coiled around the alternating strand-wires by the spindles Q.

In order to impart longitudinal movement to the spindles R during said operation to 25 prevent superposing of the coils, the spindle-yokes f' are carried by arms s', secured on the rock-shaft 50. On said shaft is an arm 31, having a roller 32, which by the weight 33, suspended from the end of said arm, is held 30 against cam 34 on shaft 35. The rotation of cam 34 vibrates arms s', and so retracts the spindles R in their boxes k' as the coiling of the picket-wire on the strand-wire progresses.

Third. The coiling-spindles S of the third 35 tier and associated parts are constructed as follows, Figs. 6, 7, and 8: The shaft E' serves as a pivot for two swinging members F', Fig. 2, and G', Figs. 6 and 2^a, having downwardly-inclined arms A', carrying rollers which bear 40 upon cam 36 on shaft 35, so that by the rotation of said shaft the frame formed by said swinging members F' G' and the downwardly-flanged connecting-beam I' is caused to vibrate on said shaft E' as an axis.

45 The coiling-spindles S are reversely placed with respect to spindles Q and R, so that the forward movement of the strand-wires will itself carry the ends p q of the pickets under their coiling-pins. They are rotated in the 50 following manner: On the upper side of cross-beam I' are mounted short shafts each carrying a spur and bevel pinion 86. The straight parts of said pinions engage with the pinions 85 on the spindles S, and the beveled parts of 55 said pinions engage with beveled pinions u, carried by a shaft v, supported on standards w on the side members of the main frame. Rotation of said shaft v therefore causes simultaneous rotation of all the spindles S.

60 In order to prevent superposing of the coils, the spindle-boxes 51 have dovetail flanges x, Fig. 8, which are received in ways on the under side of the flanges of cross-beam I', so that said boxes may be moved to and fro longitudinally, carrying the spindles with them.

To effect this movement, the rock-shaft J', extending longitudinally through beam I', is provided with tappets K', engaging, respectively, with the spindle-boxes 51, Fig. 8. On said shaft J' is an arm L', carrying a roller 70 M', which bears on a cam 81 on shaft v. The rotation of shaft v therefore causes a vibration of the rock-shaft J' and a retraction of the spindle-boxes 51 while the spindles S are in operation to coil the picket-wires on the 75 strand-wires.

Particular attention is now called to the fact that the spindles S and their boxes are radially slotted, as shown at 52, Fig. 8. When the frame before mentioned comprising the swinging members F' G' and cross-beam I' is in its lowest position, the slots 52 come over and receive the strand-wires, so that said wires then pass centrally through the spindles. This is their position during 85 the coiling operation. When the said frame is, however, raised by its cam, then the coiling-spindles S are wholly above the strand-wires and do not operate to connect any picket-wires thereto. The strand-wires carrying attached pickets then freely move onward below said spindles.

The crimping device.—This is located in rear of the third tier S of coiling-spindles and is best shown in Figs. 4 and 5. As here 95 illustrated, the crimps are produced in the strand-wires at the points of junction with the pickets. The crimps are formed by means of dies. The upper dies j' are secured between the fixed parallel bars l', which extend across 100 and are bolted to the side frame members. The lower dies m' are secured between parallel bars n', which bars move vertically on fixed guides o' in said frame members. Between the bars m' is bolted a horizontal bar 105 t', which rests upon one arm u' of a bell-crank lever, the other arm v' of which carries a roller w', which bears on cam 71, Figs. 31 and 32, on the rotating shaft 35. The dies may be laterally adjusted by set-screws y'. By 110 the rotation of shaft 35 the lower die is brought up to the upper die. The projections on the upper die then force the wire into the recesses on the lower die, thus producing the desired crimps, as shown at z', Fig. 4.

The feeding device for the strand-wires.
Fig. 1.—This is located in rear of the crimping device just explained. The several strands to which the pickets are attached pass over sprocket-wheels N' on a transverse 120 shaft, on which shaft is a ratchet-wheel P', which is operated, as hereinafter described, by a pawl Q', Fig. 1, to rotate said shaft and sprocket-wheels, and thereby to draw the strand-wires intermittently onward through 125 the machine.

The device for feeding the picket-wires L M N O P.—Upon the frame of the machine, Fig. 2^a, are six fixed parallel bars R'. Upon these slide gripping devices S', Figs. 15 and 130

16, one for each of the picket-wires. Each device S' has a plate T' with sleeves to receive two adjacent bars R'. On its upper side is pivoted a vibrating arm U', in which is secured 5 the inclined gripping-bar W'. On the face of plate T' is a block X'. The wire, as O, passes between the gripping-bar W' and the block X', and the arm U' is vibrated by a rod 38. When the rods 38 are moved in the direction of the arrow, Fig. 15, the picket-wires are first engaged between the gripping-bars W' and the blocks X', and then further motion of said rods causes the plates T' to slide 10 upon the bars R', thus moving the picket-wires transversely across the strand-wires. After a sufficient quantity of the picket-wires has been fed to form pickets the rods 38 move in the reverse direction, thus moving the gripping-bars W' away from the wires, which 15 wires now remain stationary, the plates then sliding in the reverse direction.

The cutting-off devices for the picket-wires.—These are illustrated in Figs. 13 and 14. At Y', Fig. 2, are shown six rock-shafts pivoted 20 in the frame of the machine and each provided with a lever Z', Fig. 3. All of the levers Z' are pivoted to the rod 39, so that by moving said rod to and fro said shafts are simultaneously rocked. The cutting-off device has a plate 40 provided with sleeves through which the rock-shafts Y' pass and with a guide-tube 41 for the picket-wire. The cutting-tool 42 is secured in the arm 43, which is fast on one of the rock-shafts Y'. 25 The said shafts are vibrated in one direction to bring the tool down on the wire, and so cut it, and in the other direction to permit further feeding of the wire through the guide-tube.

I will now describe the second part of the 30 machine, being the mechanism whereby the before-described devices are operated in proper time and relation.

Referring to Fig. 3, motion from shaft of belt-pulley 83 is transmitted by gears 45 to 35 shaft 22. On this shaft are the various cams which actuate the devices hitherto explained, as follows:

Cam 44, Figs. 25 and 26: This actuates the feeding devices for the picket-wires. As it 40 rotates it meets rollers 45 46 in bar 47, Fig. 3, the ends of which bar are pivoted in adjustable sliding bearing 88 89 in the vibrating pivoted standards 48 49. Said standards carry toothed sectors 52, which engage with the 45 downwardly-projecting teeth on rack-bar 53. Said bar has side teeth 54, Fig. 2, which engage a toothed sector 55 on one arm of a bell-crank lever 56, carried by the vertical rock-shaft 57, Fig. 3. The other arm of said bell-crank is connected to the rods 38, which as 50 already explained, actuate the gripping-blocks S', Figs. 15, 16.

Cam 58, Figs. 21 and 22: The lower member 59 of a swinging triangular frame pivoted 55 at 60, Fig. 1, carries at one end a roller 61,

which bears against this cam. The other end of said member 59 is pivoted to the pawl Q', which, as already explained, actuates the sprocket-wheels N', which move the strand-wires through the machine. 70

Cam 62, Figs. 19, 20: This cam drives all the coiling-spindles. It acts upon rollers 63, Fig. 1, in a bar 64, the ends of which bar are adjustably supported on screws 65 in pivoted vibrating standards 66 67. Standard 67 carries a toothed sector 68, which engages with pinion 69 on shaft 17, from which shaft by the gears W the spindles Q of the first tier are rotated. 75

Standard 66 carries a toothed sector 70, 80 which engages with a pinion on shaft E', from which, as already described, motion is transmitted to spindles R. On shaft E' is a sprocket-wheel from which by belt 72 motion is transmitted to shaft v, Fig. 8, from which, as already 85 explained, the spindles S are rotated.

Cam 73, Figs. 23, 24: This cam operates the cutting-off devices T for the picket-wires. It has a face-groove 74, in which is received a roller 75 on the end of the lever 76, Fig. 3, 90 which is pivoted at 77. Said lever is connected to the end of bar 39, which unites the arms Z' of rock-shafts Y'.

Motion is transmitted to shaft 35, and hence to cams 34-36, by chain belt 78, Fig. 1, which 95 passes over pulleys on said shaft 35 and shaft 22 and over an idler-pulley 79, adjustable in standard 80.

At 82, Fig. 1, are shown the usual rolls for straightening the strand-wires before they 100 enter the machine.

The operation of the machine.—The strand-wires B D F H J pass from the straightening-rolls 82 through the coiling-spindles Q between the dies of the crimping device, and so 105 to the sprocket-wheels N', which intermittently draw them onward. The alternating strand-wires A C E G I K come angularly upward from below the machine, pass through the inclined coiling-spindles R, and then pass to the crimping device and said sprocket-wheels N'. The transverse or picket wires L M N O P are fed across the strand-wires and are coiled, respectively, around said wires by the coiling-spindles Q. The cutting devices then cut off 110 said picket-wires to form the separate pickets, as X Y, the ends p q and p' q' of which lap over and extend beyond said strand-wires B D F, &c. The distance between the pickets on each strand-wire B D E, &c., is the same, (say 115 nine inches;) but by reason of the diagonal placing of the spindles Q the distance between the picket ends which are coiled upon the intermediate wires C E G, &c., is one-half the above interval, or four and one-half inches. 120 The spindles R S operate simultaneously to coil the ends of the pickets of two cross-rows, (one row including pickets X, the other pickets Y,) distant four and one-half inches apart, around the strand-wires A C E G I K. 125 130

Consequently for each operation of said spindles conjointly the strand-wires are fed forward a distance of nine inches, and to permit this forward feeding of said wires to take 5 place the spindles S are raised out of the way in the manner already described. In the machine of the Griswold and Goldthwait patent, before referred to, where there is but one set of coiling-spindles for securing the ends of 10 the pickets to the strand-wires, there is but one feed of four and one-half inches for each operation of this set of spindles. Hence by 15 the aforesaid construction I double the speed and capacity of the machine.

15 I claim—

1. In a machine for making wire fencing of the type herein set forth, means for securing both ends of two successive pickets simultaneously to the strand-wires. 20
2. In a machine for making wire fencing of the type herein set forth, means for simultaneously securing one end of each of two successive pickets to a single strand-wire. 25
3. In a machine for making wire fencing of the type herein set forth, two coiling devices constructed simultaneously to coil both ends of two successive pickets to the strand-wire. 30
4. In a machine for making wire fencing of the type herein set forth, two coiling devices constructed simultaneously to coil one end of each of two successive pickets to a single strand-wire. 35
5. In a machine for making wire fencing of the type herein set forth, means for securing both ends of two successive pickets simultaneously to the strand-wires, and means for intermittently feeding said strand-wires over a distance equal to twice the interval between said successive pickets. 40
6. In a machine for making wire fencing of the type herein set forth, means for simultaneously securing one end of each of two successive pickets to a single strand-wire, and means for intermittently feeding said strand-wire over a distance equal to twice the interval between said successive pickets. 45
7. In a machine for making wire fencing, mechanism for securing the outer ends of two successive pickets respectively, to two strand-wires, and mechanism for securing the inner ends of said pickets to an intermediate strand-wire; the said mechanism operating simultaneously. 50
8. In a machine for making wire fencing, means for feeding five strand-wires C, D, E, F, G, means for coiling two successive pickets respectively around said strand-wires D, F, mechanism for securing the outer ends of said pickets to two strand-wires C, G, and mechanism for securing the inner ends of said pickets to strand-wire E; the two last-named mechanisms operating simultaneously. 55
9. In a machine for making wire fencing, a strand-wire, two pickets, and two coiling devices in line with said strand-wire: the said 60
- coiling devices being constructed and operating to secure one end each of said pickets simultaneously to said strand-wire. 65
10. In a machine for making wire fencing, mechanism for securing simultaneously the outer ends of two successive pickets respectively to two strand-wires, mechanism for securing the inner ends of said pickets to an intermediate strand-wire, the said mechanisms operating simultaneously, and means for intermittently feeding said strand-wires over a distance equal to twice the interval between said successive pickets measured on said intermediate wire. 70
11. In a machine for making wire fencing, mechanism for securing two successive pickets respectively around two strand-wires D, F, mechanism for securing the outer ends of said pickets to two strand-wires C, G, mechanism for securing the inner ends of said pickets to strand-wire E, the said two last-named mechanisms operating simultaneously, and means for intermittently feeding said strand-wires C, D, E, F, G over a distance equal to twice the interval between said successive pickets measured on wire E. 75
12. A tubular, longitudinally-slidable coiling-spindle, constructed to receive a wire and to coil a second wire thereon, means for moving said second wire laterally into engagement with said spindle, means for rotating said spindle, and means for longitudinally moving the said spindle during the coiling operation. 80
13. A tubular, longitudinally-slidable coiling-spindle, constructed to receive a wire and to coil a second wire thereon, means for feeding said second wire, means for moving said second wire laterally into engagement with said spindle, means for rotating said spindle, and means for longitudinally moving said spindle during the coiling operation. 85
14. A tubular, rotary coiling-spindle, constructed to receive a strand-wire and to coil a picket-wire thereon, a vibrating finger in front of said spindle and means for intermittently actuating said finger to move said picket-wire in engagement with said spindle. 90
15. A tubular, rotary coiling-spindle, constructed to receive a strand-wire and to coil a picket-wire thereon, a fixed transverse shaft above said spindle, a finger loose on said shaft and extending in front of said spindle, and means for intermittently vibrating said finger to move said picket-wire into engagement with said spindle. 95
16. In a machine for making wire fencing, a coiling device for securing a picket-wire upon a strand-wire disposed in the path of onward feed of said strand-wire, means for intermittently feeding said strand-wire, and means for intermittently moving said device out of said path. 100
17. In a machine for making wire fencing, 105

- a coiling device for securing a picket-wire upon a strand-wire disposed in the path of onward feed of said strand-wire, means for intermittently feeding said strand-wire, and 5 means for intermittently elevating said device above said path.
18. In a machine for making wire fencing, two coiling devices constructed simultaneously to secure one end of each of two successive pickets to a single strand-wire, means for intermittently feeding said wire, and means for intermittently moving one of said coiling devices away from said wire to permit free passage of an attached picket.
19. In a machine for making wire fencing, a pivoted frame, a tubular rotary coiling-spindle mounted thereon and provided with a longitudinal radial slot constructed to receive a strand-wire, means for swinging said frame upwardly to move said spindle away from said strand-wire, and means for moving said spindle longitudinally during its coiling operation.
20. In a machine for making wire fencing, means for feeding two strand-wires, and two tubular coiling-spindles respectively receiving said wires and constructed to secure picket-wires thereon, one of said coiling-spindles being inclined in a vertical plane to the other.
21. In a machine for making wire fencing, means for feeding two strand-wires and two tubular coiling-spindles respectively, receiving said wires, and constructed to secure picket-wires thereon: one of said spindles

having its rear end depressed below the plane 35 of the strand-wire traversing the other spindle.

22. In a machine for making wire fencing, means for feeding a plurality of strand-wires, and tubular coiling-spindles respectively receiving 40 said wires and constructed to secure picket-wires thereon, the said spindles being disposed in two transverse rows, and the spindles of every alternate strand-wire being inclined to the plane passing through the axes 45 of the remaining spindles.

23. In a wire-fence-making machine, mechanism for moving five strand-wires C, D, E, F, G in a longitudinal direction, mechanism for moving a picket-wire O across the strand-wires C, D, E, 50 mechanism for moving a second picket-wire N across the strand-wires E, F, G, mechanism for securing said picket-wire O upon strand-wire D, and said picket-wire N upon strand-wire F, mechanism for 55 cutting said picket-wires to form pickets X, Y, and mechanism for simultaneously securing the ends of picket X upon strand-wires E and G, and the ends of the next succeeding picket Y upon strand-wires C and E. 60

In testimony whereof I have signed my name to this specification in the presence of two subscribing witnesses.

WILLIAM DANIEL FERRIS.
